UNITED STATES PATENT OFFICE.

CHARLES P. BRUCH, OF NEW YORK, N. Y.

DESIGN FOR A LETTER-HEAD OR SIMILAR ARTICLE.

SPECIFICATION forming part of Design No. 36,369, dated June 16, 1903.

Application filed April 29, 1903. Serial No. 154,895. Term of patent 14 years.

To all whom it may concern:

Be it known that I, CHARLES P. BRUCH, a citizen of the United States, residing in the city of New York, county and State of New York, have invented a new, original, and ornamental Design for Letter-Heads and Similar Articles, of which the following is a specification, reference being had to the accompanying drawing, forming part thereof.

10 The nature of my design is fully represented in the accompanying illustration, to which reference is made.

Having described my invention, what I claim as new, and desire to secure by Letters Patent, is—

15 The ornamental design for a letter-head, or similar article.

In testimony whereof I have signed my name to this specification in the presence of two subscribing witnesses.

CHARLES P. BRUCH.
